US00D847258S

(12) United States Design Patent (10) Patent No.: US D847,258 S
(45) Date of Patent: * Apr. 30, 2019

(54) ADHESIVE TAPE

(71) Applicant: Heejoong Kang, Gyeonggi-Do (KR)

(72) Inventor: Heejoong Kang, Icheon-si (KR)

() Term: 15 Years

(21) Appl. No.: 35/504,349

(22) Filed: Jul. 23, 2017

(80) Hague Agreement Data

Int. Filing Date: Jul. 23, 2017

Int. Reg. No.: DM/099225

Int. Reg. Date: Jul. 23, 2017

Int. Reg. Pub. Date: Jan. 26, 2018

(51) LOC (11) Cl. 19-99

(52) U.S. Cl.

USPC D19/69

(58) Field of Classification Search

USPC D19/69; D10/71; D24/189; D5/99;
D7/585; D13/182

CPC C08F 220/18; B65H 35/00; B65H 27/00
